(57) CLAIM

The ornamental design for a shaving product package, as shown and described.

DESCRIPTION

FIG. 1 is a perspective view for a shaving product package showing my new design;

FIG. 2 is a top view thereof;

FIG. 3 is a bottom view thereof;

FIG. 4 is a front view thereof;

FIG. 5 is a rear view thereof;

FIG. 6 is a left view thereof; and,

FIG. 7 is a right view thereof.

The broken line showing of a shaving product package is included for the purpose of illustrating environmental structure and forms no part of the claimed design.
